BOTTOM CONNECTION SCREW THROUGH
SETTING TOOLHarold C. Block and Leslie A. Layne, Houston,
Tex.; said Block assignor to said Layne

Application September 25, 1937, Serial No. 165,635

6 Claims. (Cl. 166—20)

The invention relates to a combination setting tool and operating device for closing the wash valve when setting a well bottom assembly.

In landing a well bottom which usually includes a set shoe, strainer, liner and packer in position in the well bore it is desirable to completely close the lower end of the well bottom assembly after the washing operation has been completed so that there will be no inflow of foreign material into the strainer. It is also desirable to suspend the well bottom from a point adjacent its lower end while it is being positioned in the well bore because in this manner the setting and washing operation can be completed and the setting string used as a flow tubing without other operations such as removing the setting string and inserting the tubing.

It is one of the objects of the present invention to provide a setting string which is connected at the lower end of the well bottom and which will be released by a rotation of the setting string so that positive release of the setting string from the well bottom assembly is assured.

It is another object of the invention to attach a screw through setting tool to the base of a well bottom assembly.

Still another object of the invention is to manipulate the wash valve and set a well bottom assembly with a screw through setting tool which is connected to the lower end of the assembly.

Still another object of the invention is to release a screw through setting tool from the lower end of a well bottom and to thereafter use the setting string for closing the wash valve of the assembly.

A still further object of the invention is to provide an apparatus for setting a well bottom assembly wherein a signal is transmitted to the operator when the well bottom has been completely set and the wash valve closed.

Still another object of the invention is to utilize a screw through setting tool to position a well bottom, close the wash valve and set the packer so as to complete the well in a single operation.

Other and further objects of the invention will be readily apparent when the following description is considered in connection with the accompanying drawings, wherein:

Fig. 1 shows a side elevation of the upper end of the well bottom assembly with certain parts in section and illustrating the arrangement as the device is being lowered into the well bore.

Fig. 2 shows the lower end of the assembly and is a continuation of Fig. 1.

Figs. 3 and 4 are similar to Figs. 1 and 2 respectively and illustrate the arrangement of the parts after the well bottom has been set, the tool released, the wash valve closed and the packer set.

The present invention relates to the general type of screw through setting tool shown in Patent No. 1,870,779, granted to Leslie A. Layne et al. on August 7, 1932, and also to the general combination of structure disclosed in the application for patent of Leslie A. Layne and Harold C. Block, Serial No. 122,948, filed January 29, 1937, for a Packer and setting tool.

In Fig. 1, the well casing is illustrated at 2 and the well bottom assembly 3 is lowered therethrough so as to project below the lower end 4 of the casing.

This well bottom assembly includes the set shoe 5 which carries a seating ring 6 and a back pressure valve 7. The inside periphery 8 of the seat ring 6 is cylindrical in order to receive the wash valve 9 which is slidably arranged within the nipple 10 which forms part of the set shoe 5.

Above the nipple 10 the strainer 11 extends and may include a suitable number of strainer sections 12. Above the strainer is the liner 13 which carries a stop 14 against which the packer 15 abuts. Projecting downwardly inside of this well bottom assembly is the setting string or tubing 17 which carries a packer setting portion 18 and extends downwardly to the elevation of the wash valve 9 where it terminates in a sleeve 19. This sleeve 19 carries a collar 20 which is releasably attached to the sleeve 19 by the shear pins 21. An anti-friction bearing 22 is mounted below the collar 20 and is arranged to abut against the shoulder 23 of collar 24. This collar at its lower end is formed with a plurality of spring fingers 25 each of which is formed with a threaded area 26 on its outer lower end. This threaded area 26 engages with a complementary area 27 on the inside of the nipple 10. These spring fingers are held in connected position as seen in Fig. 2 by means of the wash valve 9 which has a cylindrical surface 28 to abut against the inside of the fingers. The wash valve is normally held in this position by one or more shear pins 30 which project through the nipple 10 into the wash valve. This entire structure including all the parts carried by the pipe 17 comprises what is generally known as a setting tool.

This particular type which includes the threaded areas 26 and 27 is known as a screw through setting tool because the portion 19 screws through the portion 24 to release the tool.

In assembling this apparatus at the surface the set shoe, strainer, liner and packer are assembled with the wash valve 9 and the collar 24 in position. Then the setting string 17 carrying the collar 20 and sleeve 19 is lowered downwardly inside of the assembly until the sleeve 19 passes inside of the collar 24. The periphery of the sleeve 19 carries a coarse thread 35 which

matches with a corresponding coarse thread 36 inside of the collar. Rotation of the setting string 17 engages these threads and the operator may turn the setting string very slowly until the 5 shoulder 23 abuts against the bearing 22.

This engagement advises the operator that his setting tool is made up and he can then lower the entire assembly downwardly into the well bore by suspending it on the threads 26 on the 10 setting string of pipe 17.

When the parts arrive at the desired elevation the shoe 5 will rest upon the bottom and the weight of the well bottom assembly will cause the shoe to remain stationary while rotation is 15 imparted to the setting string 17. This rotation causes an additional advance of the sleeve 19 through the collar 24 so that the sleeve moves downwardly and the collar 20 is held against downward movement by the anti-friction bearing 22. A sufficient rotation will shear the pins 21 and the operator is thus advised that his setting 20 tool is screwing through because it moves down so that as soon as the threads 35 are released the setting tool can be lowered a sufficient amount 25 so that the beveled face 40 on the lower end of the sleeve 19 will abut against the shoulder 41 on the inside of the wash valve 9. During this movement the sleeve 19 will slide through the collars 20 and 23. The weight of the setting 30 string 17 may now be applied to the shoulder 41 so that the pins 30 may be sheared. Shearing of the pins 30 releases the valve 9 so that further lowering of the string 17 presses the valve 9 downwardly to the position shown in Fig. 4 35 so that the tapered sealing face 45 on the outside of the valve 9 will be wedged against the face 8 of the seat ring 6. As seen in the drawing Fig. 2 the wash valve 9 has served as an expander block by holding the fingers 25 in engagement with the threads 27 of the shoe. 40

When the valve or block moves down the fingers 25 spring inwardly and the setting tool and setting string are released from the shoe, strainer and packer. A set of slip jaws 46 wedge against 45 the inside of the nipple 10 and prevent displacement of the wash valve. This action completely closes the lower end of the well bottom assembly so that there can be no inlet of foreign material.

It will be understood that prior to the closing 50 of the wash valve that a circulation of washing liquid had served to wash the well and in the operation of this device the pressure tending to circulate this liquid is preferably maintained during the screw through action and also during the lowering operation to move the wash valve. 55 In this manner when the wash valve moves to the closed position of Fig. 4, further circulation is cut off and a jump in pressure on the gauge at the surface will instantly signal the operator that his wash valve is positively closed. This is 60 a very definite indication that the wash valve is closed because there is no other manner in which the liquid could be cut off.

As soon as this indication has been received 65 by the operator that his valve is closed, he may raise the setting string 17 so as to withdraw the lower end of the sleeve 19 from within the skirt 48 formed on the upper end of the wash valve 9. As soon as this seal is broken, there will be a 70 drop in pressure on the pressure gauge because the liquid on the inside of the pipe can then flow into the area 49 inside of the strainer 11. This drop in pressure insures the operator that his setting string is entirely free from the wash valve and the setting string can then be raised

so that the setting tool 18 is moved to the elevation of the recess 50 in the upper end of the packer 15. The packer setting portion 18 will snap into the recess 50 and upon lowering of the setting string and abut the shoulder 51 so that pressure can be applied to the packer barrel 52 to telescope it downwardly inside of the ratchet fingers 53 to collapse the packing material 54 as seen in Fig. 3. This packer 15 is known as an upside down packer and is readily set by a light weight setting string or tubing 17 because of the fact that the packer barrel 52 supports the packing 54 and telescopes downwardly inside of it so that the expanding action begins at the base of the packing and progresses 15 upwardly.

The upper end of the packer may be closed by the apron 56 which fits snugly about the setting string and prohibits the entrance of sediment or other foreign material to the inside of the 20 strainer.

It seems obvious that an apparatus has been provided whereby release of the tool is accomplished by rotation and the closing of the wash valve is accomplished by thereafter lowering the 25 wash line or setting string so that each operation is performed by a separate movement which will not effect the other operations and in each instance a signal is transmitted to advise that that operation is completed.

Broadly, the invention contemplates a combination of structure wherein the well bottom may be landed, the well washed, the bottom of the assembly closed, a signal transmitted to the operator that he has obtained a perfect closure, 35 and a further signal to indicate that his tool is released from the well bottom so that he can then proceed to set the packer, all in a single operation.

What is claimed is:

1. The combination of a wash pipe, a setting tool threaded thereon, a set shoe, an expander block holding said tool connected to said shoe, and inter-engaging means on said pipe and block to be engaged upon release of said threads to 45 move said block.

2. The combination of a wash pipe, a setting tool threaded thereon, a set shoe, an expander block holding said tool connected to said shoe, and valve means on said block to close said shoe 50 upon the movement of said block.

3. The combination of a wash pipe, a setting tool threaded thereon, a set shoe, an expander block holding said tool connected to said shoe, and shear means to releasably hold said tool 55 against unthreading from said pipe.

4. The combination of a wash pipe, a setting tool threaded thereon, a set shoe, an expander block holding said tool connected to said shoe, and an antifriction bearing between said tool and shear means.

5. The combination of a wash pipe, a setting tool threaded thereon, a set shoe, an expander block holding said tool connected to said shoe, and shear means to releasably hold said block 65 against displacement.

6. The combination of a wash pipe, a setting tool threaded thereon, a set shoe, an expander block holding said tool connected to said shoe, shear means to releasably hold said block against displacement and an upside down packer to be 70 set by said setting tool.

HAROLD C. BLOCK.
LESLIE A. LAYNE.
